SELF-ADJUSTING CHAIR

Aureo Rivera, New York, N. Y.

Application February 12, 1946, Serial No. 647,022

7 Claims. (Cl. 155—57)

1

The present invention relates to chairs and is more particularly concerned with office chairs of the swivel type.

The primary object of the invention is to provide a chair of the character referred to which will be self-adjusting in relation to a desk or table when occupied.

Another object of the invention is to provide a chair which is self-adjusting in relation to another object, such as a desk or table, but will move away from the object when vacated.

A further object of the invention is to provide a self-adjusting swivel chair with means for adjusting the plane of the seat to afford a comfortable pitch or slant thereof for the occupant.

With the foregoing and other objects and advantages in view, the invention consists of the novel construction and arrangement of parts hereinafter described and claimed.

In the accompanying drawing illustrating the invention:

Figure 1 is a side elevation of the invention showing in dotted lines, its advanced adjusted position.

Figure 2 is a front elevation thereof.

Figure 3 is an horizontal section on line 3—3 of Figure 1.

Figure 4 is a vertical longitudinal section of the invention.

Figure 5 is a horizontal sectional view on line 5—5 of Figure 4.

Like numerals in the description and drawing designate the same parts of construction.

The seat 1 of the chair is supported by standard 2, which projects from a pedestal 3, preferably of metal and having suitable weight to provide a stable base for the chair. The pedestal is in the form of a truncated pyramid, having elongated sides 4 which are slanted towards the front. Inferiorly, the pedestal is provided with an elongated, rectangular recess 5, which is disposed longitudinally thereof. The bottom of the recess is on an incline extending downwardly from the rear of the pedestal to the proximity of the front, thus forming an inclined track or runway 5—a for the purpose hereinafter disclosed.

The standard 2 is provided with forwardly and downwardly extending legs 6, constructed integral therewith and formed to straddle the sides 4 of the pedestal. Normally the feet of the legs rest against said sides and serve as lateral braces for the standard. Projecting frontally and upwardly from the standard adjacent its top is an integral arm 7 which is bifurcated at the upper end and pivotally joined, as at 8, to a horizon-

tally disposed arm 9 formed integrally with a threaded spindle 10 positioned coaxially with the standard 2. The threaded part of the spindle engages a tubular extension 11 depending from a flanged metal plate 12 which is secured by screws to the under side of seat 1, at its approximate center, thus permitting swivel movement of the same.

An elevating spindle 13 is threaded into the bottom of swivel spindle 10 and turned by means of hand-wheel 14. A helical spring 15 is contained in a socket in the upper end of standard 2 and impinges said hand-wheel, thus serving as a cushion or shock absorber. The function of the spindle 13 is to regulate the pitch of arm 9 and inclination of seat 1.

The foot of standard 2 is fashioned with parallel integral flanges 16 which depend therefrom and serve as bearings for two transversely disposed axles 17 carrying dual rollers 18. These rollers rest on the inclined track or runway 5—a and are designed to traverse same under impetus of the weight of one seating himself in the chair.

Attached to the rear roller axle is one end of a metal band or ribbon 19 which is coiled on a spool 20 having integral studs mounted in a recess 21 located in the rear end of pedestal 3. To one stud of the spool is fastened the inner extremity of a coil spring 22 and the other extremity is fastened to the wall of the recess by a pin or other suitable means. The function of coil spring 22 is to exert tension on the metal ribbon 19 when the chair is occupied and thus draw the foot of standard 2 back to normal position at the top of the slide or runway when the chair is relieved of the weight of the occupant. The band or ribbon passes from the spool 20 to the roller axle over an idler 23.

A closure plate 24 is provided for the recess 21 and another one 25, with an elongated slot 26, for the recess 5 in the top of the pedestal. The latter slot permits full freedom of movement for the standard of the chair.

In operation, the pedestal 3 would be placed at an appropriate distance from a desk, table or the like, so that a person desirous of sitting down could do so without first moving the chair either backward or forward. The advantage of this to one with books or papers in his hands will be obvious. After sitting down, the mere weight of the occupant will cause the roller coaster foot of the chair standard to gravitate towards the front of the pedestal, thus bringing the seat nearer the desk or table. The distance which the roller foot 55 will move will depend largely on the wish of the

occupant. When the occupant vacates, the action of the metal band, under tension, will return the foot of the standard to normal position without pushing the chair back from the desk. If the standard is moved all the way down the incline, as shown by dotted lines in Figure 1, the legs 6 will rest on the floor, thus serving to brace the standard, as they do when resting on the sides of the pedestal.

Having thus described my invention, what I claim as new and desire to secure by Letters Patent, is:

1. A chair adapted to be supported on a floor and comprising a seat, a base resting on the floor and provided with an inclined track, a standard connected at its upper end to the seat, means for slidably mounting the lower end of the standard in the track, and yieldable means embodying a coiled metal band rotatably supported in said base and connected to said slidable mounting means, and spring means connected to said band operating to exert tension on said band for normally retaining the standard at the upper limit of said track and providing for downward movement of the standard relative to the track upon the imposition of weight on the seat and for return upward movement of the standard upon removal of such weight.

2. A chair adapted to be supported on a floor and comprising a seat, a base resting on the floor and provided with an inclined track, a standard connected at its upper end to the seat, a roller mounting on the lower end of the standard and reciprocable in the track, and yieldable means embodying a coiled metal band rotatably supported in said base and connected to said roller mounting, and spring means connected to said band operating to exert tension on said band for normally retaining the standard at the upper limit of said track and providing for downward movement of the standard relative to the track upon the imposition of weight on the seat and for return upward movement of the standard upon removal of such weight.

3. A chair adapted to be supported on a floor and comprising a seat, a base of generally rectangular outline and formed with upwardly converging sides and a track extending longitudinally of the top of the base, a standard connected at its upper end to the seat, means for slidably mounting the lower end of the standard in the track, and laterally extending legs on the standard and having their lower ends in slidable contact against the sides of the base for bracing the standard.

4. A chair adapted to be supported on a floor and comprising a seat, a base of generally rectangular outline formed with a track extending longitudinally of the top of the base, a standard connected at its upper end to the seat, means for slidably mounting the lower end of the standard in the track, and laterally extending legs on the standard and having their lower ends in slidable contact against the sides of the base for bracing the standard.

5. A chair adapted to be supported on a floor and comprising a seat, a base of generally rectangular outline and formed with upwardly converging sides and an inclined track extending longitudinally of the top of the base, a standard connected at its upper end to the seat, means for slidably mounting the lower end of the standard in the track, yieldable means on the base and associated with the lower end of the standard,

10 said yieldable means normally retaining the standard at the upper limit of said track and providing for downward movement of the standard relative to the track upon the imposition of weight on the seat and for return upward movement of the standard upon removal of such weight, and laterally-projecting legs on the standard and having their lower ends in slidable contact against the sides of the base for bracing the standard.

15 6. A chair adapted to be supported on a floor and comprising a seat, a base of generally rectangular outline and formed with upwardly converging sides and an inclined track extending longitudinally of the top of the base, a standard connected at its upper end to the seat, means for slidably mounting the lower end of the standard in the track, yieldable means on the base and associated with the lower end of the standard,

20 said yieldable means normally retaining the standard at the upper limit of said track and providing for downward movement of the standard relative to the track upon the imposition of weight on the seat and for return upward movement of the standard upon removal of such weight, and laterally-projecting legs on the standard and having their lower ends in slidable contact against the sides of the base for bracing the standard.

25 7. A chair adapted to be supported on a floor and comprising a seat, a base of generally rectangular outline and formed with upwardly converging sides and an inclined track extending longitudinally of the top of the base, a standard connected at its upper end to the seat, means for slidably mounting the lower end of the standard in the track, yieldable means on the base and associated with the lower end of the standard,

30 said yieldable means normally retaining the standard at the upper limit of said track and providing for downward movement of the standard relative to the track upon the imposition of weight on the seat and for return upward movement of the standard upon removal of such weight, and legs on the standard projecting laterally and forwardly thereof and having their lower ends in slidable contact against the sides of the base, said legs, upon movement of the standard to the lower limits of the track being adapted to

35 extend forwardly of the base into contact with the floor.

8. A chair comprising a seat, a base, a standard connected with the base at its lower end, an arm projecting at an upward angle from the upper end of the standard, a threaded extension on the under side of the seat and comprising a laterally extending member pivotally connected with said arm, a spindle mounted on and projecting upwardly from said upper end of the

40 standard and threadedly connected with said threaded extension, and means for rotating the spindle to tilt the seat at a desired angle.
